INVENTOR:

Ludwig Schwarzmayr

UNITED STATES PATENT OFFICE

2,382,179

REFLECTOR SUPPORT

Ludwig Schwarzmayr, San Francisco, Calif.

Application July 14, 1944, Serial No. 544,991

1 Claim. (Cl. 240—78)

My invention relates to improvements in reflector supports of the type illustrated and described in an application filed by me on January 12, 1943, Serial No. 472,145; and the objects of my improvement are a construction of a spring-finger reflector support which retains operating efficiency after long use, and which at all times engages the globe at a circle spaced from its major circle but relatively close thereto when adjusted to a loosely slideable position, so as to facilitate adjustment of the reflector support from the loosely slideable position to secured position.

I attain these objects by the construction illustrated in the accompanying drawing in which—

Figure 1 shows the new reflector support mounted on the globe in a secured position and supporting a reflector, the reflector and the reflector support are shown in section.

Fig. 2 shows the reflector support on the globe in a loosely slideable position in which the spring-fingers engage the globe on a circle spaced from its major circle.

Fig. 3 is a detailed view of a segment of the reflector support shown in Figs. 1 and 2.

Fig. 4 is a detailed view of the reflector support on line 4—4 in Fig. 3, and showing a segment of the globe with which the spring-fingers of the reflector support is in loosely slideable relation, similar to that in Fig. 2.

Similar numerals refer to similar parts throughout the several views.

The conduit 1 supports the globe 2 and the light source 3. A rigid annular member 4 supports the reflector 5, and is dimensioned to be supported by the surface of the globe spaced from its major circle 6, as it is shown in Fig. 1. From the annular member 4 extend spring-fingers 7, 7, which engage the globe 2 about its major circle 6 under stress, whereby they sup-

port the reflector 5 in position. When the reflector support 4 is lifted to the position shown in Figs. 2 and 4 the inward movement of the spring-fingers 7 is limited by the rigid flange 8 extending down from the reflector supporting member 4, so that the spring-fingers 7 engage the globe 2 loosely slideable on the circle 9 of the globe, whereby they are relatively close but spaced from the major circle 6 so as to facilitate adjustment of the reflector from the loosely slideable position, shown in Fig. 2, to the secured position, shown in Fig. 1. The spring-fingers 7 are of a construction causing them to engage the flange 8 under stress, so that they retain their operative efficiency when in long use, and so that they engage the globe at a circle spaced from its major circle 6 but relatively close thereto when in loosely slideable position.

This new reflector support is adjustable in the same manner as the reflector support described in the above referred to application.

I claim:

In a reflector support, a globe, a rigid annular member and a reflector supported thereby, said member being dimensioned to be supported by said globe spaced from its major circle and having spring-fingers extending downwardly therefrom and being adapted to engage said globe under stress about its major circle and being upwardly movable to a loosely slideable position on said globe spaced from said major circle, and a rigid flange extending downwardly from said member and limiting the inward movement of said spring-fingers to cause the spring-fingers to engage said globe loosely slideable on a circle spaced from said major circle but relatively close thereto.

LUDWIG SCHWARZMAYR.
